US0D1012625S

(12) United States Design Patent (10) Patent No.: US D1,012,625 S
(45) Date of Patent: * Jan. 30, 2024

(54) GAME SNACK CHOPSTICKS

(71) Applicant: Hangzhou Xingxin culture media Co., Ltd., Hangzhou (CN)

(72) Inventor: Guoping Lao, Hangzhou (CN)

() Term: 15 Years

(21) Appl. No.: 29/802,101

(22) Filed: Aug. 3, 2021

(51) LOC (14) Cl. 07-03

(52) U.S. Cl.

USPC D7/642

(58) Field of Classification Search

USPC ..... D7/368, 401.2, 642–645, 653–664, 669, D7/675–677, 683, 686–689, 691; D8/107, 300–301; D22/117–118 CPC ... (57) CLAIM

The ornamental design for game snack chopsticks, as shown and described.

DESCRIPTION

FIG. 1 is a top, front and right side view of game snack chopsticks showing my new design;

FIG. 2 is a front view thereof;

FIG. 3 is a rear view thereof;

FIG. 4 is a right view thereof;

FIG. 5 is a left view thereof;

FIG. 6 is a bottom view thereof;

FIG. 7 is a top view thereof; and,

FIG. 8 is a top, rear and left side view of thereof.

1 Claim, 8 Drawing Sheets
